(57) **CLAIM**

The ornamental design for a bottle, as shown and described.

DESCRIPTION

FIG. 1 is a top, rear perspective view of a bottle in accordance with a first embodiment of our new design;

FIG. 2 is a bottom, front perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, rear perspective view of a bottle in accordance with a second embodiment of our new design;

FIG. 10 is a bottom, front perspective view thereof;

FIG. 11 is a rear elevation view thereof;

FIG. 12 is a front elevation view thereof;

FIG. 13 is a left side elevation view thereof;

FIG. 14 is a right side elevation view thereof;

FIG. 15 is a top plan view thereof; and,

FIG. 16 is a bottom plan view thereof.

In the drawings, the broken lines show portions of a bottle that form no part of the claim. The oblique shade lines represent claimed surfaces that are transparent or translucent.

1 Claim, 16 Drawing Sheets
